CABINET AND SUPPORT FOR CONTAINERS

Ever A. Ferm, Chicago, Ill.

Application December 17, 1948, Serial No. 65,885

2 Claims. (Cl. 312—283)

1

This invention relates to storage apparatus, and more particularly to cabinets and supports for containers which are particularly adapted for the storage of odoriferous materials, such as garbage, industrial substances of various kinds, etc.

It is among the objects of the present invention to provide a cabinet and support for containers which permits ready access to the materials within the container, while at the same time providing a sanitary housing which protects against rodents, insects, etc., and exposure to the elements and to a substantial extent reduce the escape of the odors from the stored materials.

Another object is the provision of a device of the class described which is attractive in appearance, efficient and durable in service and comparatively simple and inexpensive to manufacture and install.

The invention, then, comprises the features fully described and as particularly pointed out in the claims, the following description and annexed drawings setting forth in detail an illustrative embodiment of the invention, this being indicative of but one of a number of ways in which the principles of the invention may be employed.

In said drawings:

Figure 1 is a plan of the combined cabinet and container support of the present invention, showing the latter in extended position whereby ready access to the supported container may be had.

Figure 2 is an elevation of the showing of Figure 1.

Figure 3 is a front elevation showing the container support in its retracted position.

Figure 4 is an elevation taken from the right-hand side of the showing of Figure 3.

Figures 5 and 6 are foreshortened elevations corresponding to Figures 3 and 4, respectively, but illustrating the mounting of the cabinet on a concrete slab.

Referring more particularly to the drawings, the numerals 1 and 2 respectively designate the top and bottom of the cabinet.

As shown most clearly in Figure 1, the top and bottom members 1 and 2 are substantially rectangular in plan with one corner defined by a diagonal edge of substantial length.

One side (the left side of Figures 1 and 2) and the back of the cabinet are formed by ad-

2

joining and right-angularly disposed vertically extending panels as indicated at 3a and 3b.

A side panel 3c is disposed opposite the side panel 3a and likewise adjoins the back panel 3b and extends at right-angles to it. However, this side panel 3c is much narrower than the side panel 3a, as shown. Correspondingly, a front panel 3d is disposed opposite the back panel 3b, adjoining the front edge of the side panel 3a and extending at right-angles with respect to it. As shown in Figures 1 and 2, the front panel 3d is much narrower than any of the other panels, including the narrow side panel 3c.

The top member 1 and the bottom member 2 are provided with vertically disposed and aligned short tubular members 4 and 5 respectively which are disposed in a vertical plane which extends transversely of the cabinet at the approximate center thereof; and a corresponding but much longer tubular member 6 is disposed between, and in alignment with foreshortened tubular members 4 and 5. A vertical rod 7 connects the foreshortened tubular members 4 and 5 and the intermediately disposed elongate tubular member 6; and is secured against rotation in any suitable manner. The rod 7 also acts as a brace between the upper and lower members 1 and 2, which possesses no support between the panels 3c and 3d other than the door structure described below.

The door of the cabinet and container support comprises a series of angularly disposed and endwise connected horizontally extending upper framing members 8 and a series of correspondingly shaped and connected lower framing members 9. As shown in Figure 1, the component elements of the upper and lower series of horizontally extending and endwise connected framing members 8 and 9 are assembled at approximate 45° angles with respect to each other. The upper and lower series of framing members 8 and 9 are connected by panels 16 which form the body of the door or closure.

The inner and outer ends of the upper and lower series of framing members 8 and 9 are connected with vertical braces 11 and 12, respectively. These braces together with the door panels 16 and the tubular member 6, which is connected to corresponding upper and lower framing members, afford sufficient rigidity to

support a platform or tray 13 mounted on the inner side of the door, and attached to the lower series of framing member 9 and a loaded container carried on said platform.

As shown at the bottom of Figure 2, a thrust bearing 18 is disposed between the upper end of the lower tubular member 5 and the adjacent portion of the underside of the lower series of framing members 9. The lower end of the intermediate and elongate tubular member 6 may, if desired, be extended into contact with the thrust bearing 18. In any case, the thrust bearing 18 effectively supports the door with the platform or tray 13 and its contents.

Adjustable pedestals 20 are provided for supporting the cabinet in proper position. In addition, the lower series of framing members 9 of the door may be provided with a depending leg 21 at the approximate center thereof in order to insure against overturning when the platform or tray 13 is heavily loaded.

For convenience, a handle 22 may be disposed at the upper left-hand corner of the door.

From the foregoing, it will be perceived that the elements of the cabinet, while of comparatively light and simple design will adequately accommodate the platform or tray 13 and the supported container X in extended or retracted position. The cabinet is capable of enclosing with a minimum of waste space a cylindrical container such as X of horizontal and vertical dimensions substantially equal to those of the cabinet, while the door and platform 13 carrying the container, can be pivoted out of the enclosed or retracted position to an extended position substantially free of the cabinet top 1 and in which the contents of the container are readily accessible from above.

The distance between the aligned tubular members 4, 5 and 6 and the adjacent edge of the narrow side panel 3c of the cabinet is substantially less than the distance between the said tubular members and the inner edge of the hingedly mounted door, whereby the offset portion of said door may swing inwardly within the cabinet and overlap the narrow side panel 3c to form a closure for that side of the cabinet; while the outer edge of the door is adapted to register with the adjacent edge of the narrow front panel 2d to complete the closure at that point.

This construction obviates the necessity for separate doors, or the like. Moreover, the arrangement of the moving parts with respect to the stationary ones is such that effective air-tight seals may be provided, this being especially desirable if the contents of the container X are odoriferous. Furthermore, deodorizing or sterilizing media (such as ultra-violet lamps) may readily be supported on the underside of the top member 1.

Another feature is that the upper surface of the top member 1 not only provides a shelf, but it encloses the hinged connection between the cabinet and the door, regardless of whether the latter is in open or retracted position, thereby eliminating exposure to the elements.

While I have shown and described certain specific embodiments of the present invention, it will be readily understood by those skilled in the art that I do not wish to be limited exactly thereto, since various modifications may be made without departing from the scope of the invention as defined in the appended claims.

I claim:

1. A cabinet comprising parallel and similarly

shaped top and bottom members which are substantially rectangular in plan with one corner defined by a diagonal edge of a length which is substantial but considerably shorter than the opposite rectangular edges of said member, adjoining and right-angularly disposed vertically extending back and side panels, a relatively narrow and right-angularly disposed vertically extending side panel adjoining said back panel, a relatively narrow and right-angularly disposed vertically extending front panel adjoining said first-named side panel, said relatively narrow front and side panels together with said top and bottom members providing between them a door opening of substantial width, a door adapted to close said opening, said door including a series of angularly disposed and endwise connected horizontally extending upper framing members and a series of angularly disposed and endwise connected horizontally extending lower framing members, panels extending between the corresponding upper and lower framing members of said door, a platform mounted on the lower series of said framing members and extending inwardly therefrom, and a vertically disposed hinged connection extending between the top and bottom members of said cabinet and pivotally connecting said door and said members, said hinge connection being offset from the vertical center-line of said door and attached to the top and bottom members of said cabinet at a point between the front edge of the narrow side panel and the diagonal edge of said members, the distance between the front edge of said narrow side panel and said hinge connection being less than the distance between said hinge connection and the vertical edge of the inwardly extending door section.

2. A cabinet comprising parallel and similarly shaped top and bottom members which are substantially rectangular in plan with one corner defined by a diagonal edge of a length which is substantial but considerably shorter than the opposite rectangular edges of said member, adjoining and right-angularly disposed vertically extending back and side panels, a relatively narrow and right-angularly disposed vertically extending side panel adjoining said back panel, a relatively narrow and right-angularly disposed vertically extending front panel adjoining said first-named side panel, said relatively narrow front and side panels together with said top and bottom members providing between them a door opening of substantial width, a door adapted to close said opening, said door including three angularly disposed and endwise connected horizontally extending upper framing members and three angularly disposed and endwise connected horizontally extending lower framing members, a panel extending between the outward edges of each of the corresponding upper and lower framing members of said door and forming the main body of said door, and relatively narrow side panels extending between the corresponding ends of the upper and lower frame, said last-named side panels disposed angularly inward with respect to the main door panel, a platform mounted on the lower series of said framing members and extending inwardly therefrom, and a vertically disposed hinged connection extending between the top and bottom members of said cabinet and pivotally connecting said door and said members, said hinge connection being offset from the vertical center-line of said door and attached to the top and bottom members of said cabinet at a

point between the front edge of the narrow side panel and the diagonal edge of said members, the distance between the front edge of said narrow side panel and said hinge connection being less than the distance between said hinge connection and the vertical edge of the inwardly extending door section.

EVER A. FERM.
